CLAIM

The ornamental design for a lie adaptor, as shown and described.

DESCRIPTION

FIG. 1 is a perspective view of a lie adaptor showing my new design;

FIG. 2 is a top perspective view thereof;

FIG. 3 is a top view thereof;

FIG. 4 is bottom view thereof;

FIG. 5 is a front view thereof;

FIG. 6 is a back thereof;

FIG. 7 is a right side view thereof; and,

FIG. 8 is a left side view thereof.
